ARTICLE FORMING AND HANDLING
MECHANISMGeorge Goebel, Baltimore, Md., assignor to Crown
Cork & Seal Company, Inc., Baltimore, Md., a
corporation of New York

Application October 18, 1938, Serial No. 235,667

5 Claims. (Cl. 113—1)

The present invention relates to an article forming and handling mechanism and, more particularly, to means for conducting formed articles from a punch press.

In the forming of substantially flat articles, such as sheet metal can tops, upon a punch press, it is desirable to keep the can tops separated when they leave the press so that they will not become nested. Such nesting is undesirable because after the tops have been punched from a metal sheet and substantially formed by the punch press, they must move in single line to a curling mechanism to have their flat edges slightly curled. If two articles should become nested immediately after the punching operation and while their edges are still flat, they cannot be separated before reaching the curling mechanism and will either both be curled simultaneously while nested, and hence permanently joined to each other, or one or both of the can tops will be deformed in the curler.

Heretofore, in forming articles such as can tops; that is, articles apt to become nested in such a way as to interfere with their subsequent handling, it has been necessary to provide but one row of dies upon the punch press and to so arrange this row of dies that the articles could not become nested when leaving the press. The use of only a single row of dies has naturally limited the output of the punch press.

The principal object of the present invention is to provide a structure including a punch press having a multiple row of dies and means to transport or move can tops or other articles from the punch press without possibility of the articles from the one row of dies becoming nested or otherwise interfering with articles formed by another row of dies.

Other objects and advantages of the invention will be apparent from the following specification in which:

Figure 1 is a view in front elevation of a punch press and curling means associated therewith, the view being taken in the direction of the arrow A of Figure 3;

Figure 2 is a plan view showing the bed plate of a punch press and the article removing means associated therewith, the view being taken from the direction of the arrow B in Figure 3;

Figure 3 is a transverse vertical sectional view taken on the line 3—3 of Figure 2;

Figure 4 is a fragmentary side view of the punch press of Figure 1, showing the article removing means in vertical section;

Figure 5 is a vertical sectional view of a can

top blank as formed by the punch press of Figure 1; and

Figure 6 is a vertical sectional view of a can top as curled and completed by the curling mechanism of Figure 1.

The numeral 10 designates a punch press including a bed plate 11 and an upper and substantially vertically reciprocating head 12. As is usual in punch presses of this type, the head 12 reciprocates with respect to the bed plate so that upper or male dies 13 carried by the moving head will coact with lower or female dies 14 to cut a disk from a sheet of metal and simultaneously form the disk to a desired shape. The sheet of metal to be cut is fed upwardly by suitable means, not shown, through a passage 15 provided between the upper face 17 of the bed plate 11 and the lower surface of a face plate 18, plate 18 having a plurality of circular openings 19 formed therein, one in alignment with each of the dies 14.

As indicated in Figures 1 and 2, the lower dies 14 are arranged in two rows 20 and 21 and since the bed plate 11 is inclined, the row 20 is beneath the row 21. Also, the dies 14 of the respective rows are staggered with respect to each other so that a die of the upper row 21 will not be in alignment with a die of the lower row 20.

A guide or conveyor plate 24 is provided to conduct from the press the can tops formed by the die elements of the lower row 20, the inner edge of this guide plate bearing upon the face plate 18 just below the lower row of cut-outs 19 thereof. The lower edges of the cut-outs 19 are beveled as indicated at 19a. Hence, when a can top is expelled from a die 14 by the movement of a portion of the die to the dotted line position illustrated in Figure 3 by usual and well-known means, that can top will slide down the plate 18 and onto the guide plate 24. The lower edge of the guide plate 24 extends to the lower run 25 of an endless conveyor 26 which run, as indicated in Figure 1, moves to the left to convey the can tops to a chute 26 down which they move to a curling mechanism 27 of usual construction.

An upper guide or conveyor plate 30 is secured at its lower edge to the frame 25a of the conveyor 25 and has its upper edge bearing upon the face plate 18. As best shown in Figure 2, the guide plate 30 has portions cut away from its uppermost portion as indicated at 31, these cut-out portions being in alignment with the dies of the lower row 20 and so spaced as to provide tongues 32 which bear upon the face plate 18

at points between the dies of the lower row 20 and along a horizontal line adjacent the upper edge of the die elements 14 of the lower row 20. By this arrangement, since the upper row of elements 21 is staggered with respect to the lower row 20, each tongue 32 will be directly beneath a die 14 of the upper row 21. Obviously, when a can top formed by any one of the die elements 14 of the upper row is expelled from such element, that can top will move directly downwardly along the face plate 18 and onto the aligned tongue 32 of upper guide plate 30 and thence downwardly to the upper run 34 of the endless conveyor 25. This run of the conveyor is moving to the right as viewed in Figure 1 and will convey the can tops to a chute 35 which leads to a second curler 36.

The conveyor 25 is driven from the press at such speed that it will be impossible for two can tops of a batch produced by either the upper row 20 of die elements or the lower row of die elements to fall upon the conveyor in nested relation. Hence, each can top will move separately to the curling mechanism and there will be no possibility of their becoming nested. The desirability of keeping the can tops separate will be understood from Figure 5, wherein an incompletely can top C of the form produced by the punch press is illustrated in vertical section. It will be appreciated from this view that two top elements C could readily become nested should one fall upon the other. Figure 6 shows a completed can top C'; that is, a top having its edges curled as indicated at CC'. Because of the curl at the edge of the completed tops, they cannot become nested and once they have moved through the curling mechanism 27 and 36, may be piled in a stack by suitable handling mechanism, not shown, provided at the outfeed of the curling mechanism.

While the structure of the present invention has been described in connection with a punch press for can tops, its broad embodiment is not limited to use with such an apparatus, the invention being applicable to any mechanism wherein articles are shaped to a form in which they may ordinarily nest or contact with each other and thereby interfere with one another during subsequent handling.

The phraseology used in the specification is not intended to limit the invention, the scope of the invention being indicated in the following claims.

I claim:

1. The combination in a punch press, of an inclined bed plate, a pair of rows of die elements, one row positioned above the other on said inclined bed plate, the die elements of one row being staggered with respect to the die elements of the other row, and a guide plate to receive articles extending from a transverse line on said bed plate substantially between the rows of die elements, said guide plate being cut away at points in alignment with the die elements of the lower row of dies.

2. The combination in a punch press, of a bed plate and a press head, a pair of rows of die sets, each set having one die element thereof carried on said bed plate and its other element carried on said press head, one row of die elements being positioned above the other on said bed plate, and a pair of guide plates for guiding formed articles

from the press, said guide plates being positioned at the side of the bed plate nearest the lower row of die elements, one guide plate being superposed with respect to the other and each guide plate having a receiving edge adjacent one row of die elements of the bed plate to receive articles formed by that row of die elements, the upper guide plate being so constructed as not to interfere with the operation of the press head die elements which cooperate with the lower row of elements on the bed plate.

3. The combination in a punch press, of a bed plate and a press head, a pair of rows of die sets, each set having one die element thereof carried on said bed plate and its other element carried on said press head, one row of die elements being positioned above the other on said bed plate, a pair of guide plates for guiding formed articles from the press, said guide plates being positioned at the side of the bed plate nearest the lower row of die elements, one guide plate being superposed with respect to the other and each guide plate having a receiving edge adjacent one row of die elements of the bed plate to receive articles formed by that row of die elements, the upper guide plate being so constructed as not to interfere with the operation of the press head die elements which cooperate with the lower row of elements on the bed plate, and upper and lower conveyors respectively positioned adjacent each of said guide plates to receive articles from the latter.

4. The combination in a punch press, of a press head and an inclined bed plate, a pair of rows of die sets, each die set having one element thereof carried on said bed plate and its other element in said press head, one row of bed plate elements being higher on the bed plate than the other, and a pair of guide plates for guiding formed articles from the press, said guide plates being positioned at the lower side of the bed plate, one guide plate being superposed with respect to the other and each guide plate having a receiving edge adjacent one row of die elements of the bed plate to receive articles formed by the corresponding row of die sets, the upper guide plate being so constructed as not to interfere with the operation of the press head die elements which cooperate with the lower row of elements on the bed plate.

5. The combination in a punch press, of a press head and an inclined bed plate, a pair of rows of die sets, each die set having one element thereof carried on said bed plate and its other element in said press head, one row of bed plate elements being higher on the bed plate than the other, a pair of guide plates for guiding formed articles from the press, said guide plates being positioned at the lower side of the bed plate, one guide plate being superposed with respect to the other and each guide plate having a receiving edge adjacent one row of die elements of the bed plate to receive articles formed by the corresponding row of die sets, the upper guide plate being so constructed as not to interfere with the operation of the press head die elements which cooperate with the lower row of elements on the bed plate, and upper and lower conveyors moving in opposite directions positioned adjacent each of said guide plates to receive articles from the latter.

GEORGE GOEBEL.
